CONDITION RESPONSIVE SWITCH

Carl G. Kronmiller and Homer E. Malone, Minneapolis, Minn., assignors to Minneapolis-Honeywell Regulator Company, Minneapolis, Minn., a corporation of Delaware

Application December 21, 1935, Serial No. 55,603

29 Claims. (Cl. 200—139)

This invention relates to a condition responsive switch, and more particularly to a switch responsive to variations in the temperature of a space.

An object of the present invention is to provide a condition responsive switch in which it is possible to make all desirable and necessary adjustments without any danger of distortion of the condition responsive element.

A further object of the invention is to provide an adjusting means for a condition responsive switch wherein a single element functions to prevent undesired movement of the adjusting means, as a means for indicating the setting of the adjusting means, and as a stop to limit the movement of the adjusting means.

A further object of the present invention is to provide a new and novel means for mounting a condition responsive switch wherein the means for mounting the same serves also as a means for making electrical connections to the switch elements.

A further object of the invention is to provide a novel mounting means for a condition responsive switch wherein the switch base is resiliently secured to the supporting surface and wherein it is impossible to distort the base by excessive tightening of the fastening means.

A further object of the invention is to provide in a switch having a plurality of pairs of contacts sequentially engaged with means for indicating the change in condition necessary between engagement of the respective pairs of contacts.

A further object of the invention is to provide in a thermostatic switch employing an associated heater, a new and novel means for mounting said heater wherein the mounting means serves as the electrical connecting means.

A further object of the present invention is to provide a cover for a condition responsive switch in which a condition indicating instrument is mounted in a manner to protect the same against damage, and in which said mounting means permits the initial adjustment of said indicating device.

Other objects of the invention will be apparent from the accompanying specification, claims and drawings, of which:

Figure 1 is a front elevational view of the condition responsive switch,

Figure 2 is a side elevational view of the switch proper taken in the direction of arrow 1 of Figure 1 with the base shown in section along the line 2—2 of Figure 1,

Figure 3 is a rear elevational view of the switch,

Figure 4 is a section along the line 4—4 of Figure 1,

Figure 5 is an elevational view of the switch contact structure with a section through the base along the line 5—5 of Figure 1,

Figure 6 is a detail view of the switch blade structure,

Figure 7 is a perspective view of the terminal wall plate by which the switch is mounted,

Figure 8 is a rear view of the terminal wall 10 plate,

Figure 9 is a section along the line 9—9 of Figure 1,

Figure 10 is a sectional view of the heater element,

Figure 11 is a schematic view of a control circuit embodying the switch,

Figures 12 and 13 are front and side elevational views of a portion of a modified form of the switch,

Figure 14 is a detailed view of a contact employed in the modified form,

Figure 15 is a perspective view of the switch assembled within the cover,

Figure 16 is a side elevational view of the cover 25 and switch assembly with portions broken away,

Figure 17 is a section taken along the line 17—17 of Figure 16,

Figure 18 is a detail view of a member employed in mounting a condition indicating device 30 within the cover, and

Figure 19 is a section along the line 19—19 of Figure 17.

Referring to Figures 1 and 2 of the drawings, the switch is shown as comprising a bimetallic 35 member 11 bent to form a U-shaped member which is pivotally mounted on a base 12. One leg of said bimetallic member is provided with a pair of contacts 14 and 15 which are best shown in Figure 5. These contacts are adapted to engage 40 with stationary contacts 16 and 17. The other leg 18 of said bimetallic member terminates in a curved cam follower 19 which engages the helical cam surface 20 of an adjusting cam 21. The means for pivotally mounting the bimetallic member 11 on the base comprises a bracket member 22 rigidly secured to said base by screws 23 and 24, shown in Figures 3 and 9. The bracket 22 pivotally supports a U-shaped member 25 which is secured to the lower leg 18 of the bimetallic element by any suitable fastening means.

As will be apparent from the drawings, the bimetallic member 11 is mounted diagonally with respect to the base 12. This permits the use of a longer bimetallic element for the same length 55

of base. There is an even more important advantage in this arrangement and that is that the bend of the U shaped bimetal member is placed at an angle such that it is more exposed to the air entering the cover of the switch no matter whether the air is introduced vertically or horizontally to the switch. Since the bend of the bimetallic element is the most sensitive portion of the same this is a highly desirable feature.

10 The cam 21 is secured rigidly to a stud 26 with a slightly tapered threaded interior, which is slotted as at 27 to make the threaded portion yieldable. The stud is threadedly engaged with the interior of a bushing 28 to the upper end of which is rigidly secured a circular scale member 29. A set screw 30 is threaded within the interior of stud 26. When the set screw 30 is not screwed into the interior of the stud 26, the latter member is in loose-threaded engagement with the bushing 28 permitting the cam 21 to be rotated with respect to the scale 29. Upon the set screw being tightened the same expands the stud with the result that the threaded engagement between stud 26 and bushing 28 is correspondingly tightened so that cam 21 can no longer be turned with respect to scale 29 and any movement imparted to scale 29 will similarly be imparted to the cam 21. As best shown in Figures 2 and 3, a friction washer 31 is provided with three resilient tongues 32, which engage the under surface of the base and yieldably urge the scale against a washer 33 which is located between said scale and the base member. Stops 34 are provided to prevent said friction washer from turning. The friction washer is further provided with an extension 35 which extends outwardly and upwardly through a slot 36 in the base and a slot 37 in the scale member 29 and terminates in a pointer 38 overlying the scale. As is clear from Figure 1 this pointer not only serves to give an indication of the adjustment of the cam but also constitutes a stop for limiting the movement of the cam by abutting with the ends of slot 31. As is usual with devices of this character, the scale is graduated in terms of degrees, although it is to be understood that the invention is not limited to a temperature responsive switch and that in the event that some other condition than temperature is to be measured, this scale will be graduated accordingly. The adjusting means has associated therewith a device for locking the same at any desired setting. This device, as shown most clearly in Figure 4, comprises a pair of clamping members 39 and 40 which are slidably located within a recess 60 in the base 12 and are held against lateral movement in the direction of rotation of scale member 29 by the walls of said recess. The members are adapted to be clamped together against the scale member 29 by means of a screw 63 in threaded engagement with member 40. After the thermostat has been set at the desired position it may be locked by tightening of the screw 63. Since the clamping members are urged with equal force against the opposite sides of the scale, the scale is not subjected to a force tending to distort the same, as when a single clamping member is employed.

70 A pair of contact mounting brackets 41 and 42 are secured to the base 12 through screws 43 and 44 as shown in Figure 5. Bracket 41, as best shown in Figure 1, is provided with a forwardly extending arm 45 which is provided with a screw-threaded aperture 46 and is slotted at 47 to resiliently engage a contact screw 48 in said aperture 46. The connection between contact screw

48 and the arm 45 is sufficiently tight that the screw can only be turned when an appreciable amount of pressure is applied to the same. In this manner there is an assurance that any adjustment that may be made will not be accidentally altered. The bracket 42 is similarly provided with a forwardly extending arm 49 corresponding to the arm 45 of bracket 41. This arm is similarly slotted and provided with a screw-threaded aperture into which a contact screw 50 is threaded. As in connection with the previously described contact and bracket structure, the engagement of the screw 50 with the aperture of arm 49 is rather tight so as to prevent accidental disturbance of the adjustment of said screw. This contact and arm structure differs from the previously described one, however, in that the contact screw is provided with a dial 51 adjacent the head of the screw which is provided with numerals or other indicating media thereon. The arm 49 is provided with a pointer 52 which cooperates with the indications on said dial to give an indication of the setting of screw 50. Extending between brackets 41 and 42 is a bar 53 of insulating material. This bar is for the purpose of limiting the outward movement of the bimetallic contact arm as will be presently described.

The bimetallic contact arm structure is best shown in Figure 6 and comprises a contact carrying member 54 which is rigidly secured to the leg 13 of the bimetallic element. The contact carrying element 54 is provided with two forwardly extending legs 55 and 56. Leg 55 carries the contact 14 which is adapted to engage with contact 16. The leg 56 has attached thereto a resilient contact blade 57 which carries the contact 15 adapted to engage with contact 17. The leg 56 is bent upwardly and extends along the upper side of the contact blade 57 spaced a sufficient distance from the same to permit flexure of the blade outwardly. The end of the leg 56 is bent around and terminates in a portion 58 engaging the under side of contact blade 57 to limit inward movement thereof. The portion 58 extending over and engaging the contact blade 57 provides a means for adjusting the tension of the resilient blade. By bending the leg 56 in either direction, the tension of the blade 57 can be changed as will be readily apparent. The contact carrying element 54 terminates in an inwardly extending hook 59 which engages the bar 53 to limit the outward movement of the leg 13 of the bimetallic element.

The means for mounting the switch to a wall or other supporting surface is best shown in Figures 7 and 8. This means consists of a terminal wall plate generally indicated by the reference numeral 61. This member comprises a supporting metallic plate 62 having ears 64 which are slotted for the reception of suitable fastening means such as screws to permit attachment of the plate to a wall or other supporting surface. The plate 62 is provided with upturned edges 65 in which is mounted a plate 66 of suitable insulating material which is secured to the metallic plate 62 by any suitable fastening means such as rivets. Mounted on the plate 66 of insulating material are three terminal members 67, 68 and 69. Each of these members is provided with a pair of tongues 70 which extend through an aperture in the insulated plate 66 and are bent over to engage the wall side of the insulated plate and secure the terminal member thereto, as most clearly shown in Figure 8. Each 75

of these terminal members 67, 68 and 69 are further provided with two ears, both of which have threaded apertures. In each case, a binding screw 71 is located in the threaded aperture of one of said ears and serves to permit the connection of an electrical conductor to said terminal. The aperture in the other ear is adapted to receive a screw 72 which is permanently secured to the switch member. As best shown in Figures 1 and 2 these screws extend through resilient arms 73 which arms are adapted to engage the terminals 67, 68 and 69 and secured thereto by engagement of screws 72 in the apertures opposite those in which binding screws 71 are located.

Mounting brackets 22, 41 and 42 are provided with ears 14, 75 and 76, respectively, as indicated in Figure 1. Each of these ears is provided with an aperture of sufficient size for the insertion of a screw driver which aperture communicates with an aperture of slightly greater diameter in the base and is located in line with one of the screws 72 so as to permit tightening of the same therethrough. While these apertures are of sufficient size to permit the insertion of a screw driver, they are not of as large a diameter as that of the heads of the screws 72 so that it is impossible for the screws 72 to pass therethrough. In this manner the screws 72 are permanently retained in assembled relation with the switch structure so that there is no danger of their being lost therefrom. It will further be noted that no matter how tightly the screws 72 are turned it is impossible to apply any stress to the base 12 and no matter how tightly these screws are tightened, the base 12 is yieldably mounted on the terminal plate 61 by reason of the yieldability of the members 13. In this way there is overcome the disadvantage of certain prior art structures wherein the insulated base 40 of the switch structure was directly connected to the wall plate and if the fastening means were excessively tightened the base of the switch structure would be distorted, disturbing the adjustment of the various settings.

It is desirable in certain cases where the condition responsive switch takes the form of a thermostatic switch to employ a heater in connection therewith to accelerate the action of the switch during a certain portion of the operating cycle.

In Figures 9 and 10 there is shown a means providing for such a heater. The heater 96, as shown most clearly in Figure 10, comprises a slotted screw-threaded metallic head 97, a pin member 98, and a sleeve of insulating material 100 which is secured to the head 97 and surrounds and engages the pin 98. Around this insulating member is wound a heater element 99 which has one end secured to a washer of conductive material in engagement with the end of the pin 98 by any suitable means that will enable a good electrical connection to be obtained, such as soldering. The other end of the heater element is similarly soldered to the head 97. The heater 96 is adapted to be located in a housing 78, which housing is interiorly threaded at its upper end to receive the threaded head 97 of the heater. The housing is retained to the base 12 by means of a screw 24. The housing is provided at its lower end with a slotted cylindrical extension 79 which is adapted to fit into a splined opening 80 in the base of bracket 22 so as to be held non-rotatably therein. The screw 24 has interposed between its head and the base of the housing 78 an insulating washer 82 and is threaded to the

base and engages at its other end the resilient member 13 which, as explained previously, is electrically connected with terminal 67. The slotted head 97 of heater 96 is screwed down sufficiently within the housing 78 so that the end of the pin 98 engages the head of screw 24. In this manner one end of the heating element 99, which is connected to this end of the pin, is electrically connected through screw 24 and resilient member 13 with terminal 67. The other end of the heater 10 element is electrically connected through the pin head 97, the housing 78, the base of bracket 22, and a jumper 81 with the bimetallic element. If for any reason it is desired not to employ a heating connection in the thermostat all that is necessary to do is to unscrew the heater unit 96, unscrew the screw 24, remove the housing 78 and the insulated washer 82 and replace screw 24, screwing it down until it enters the circular portion of the opening 80. The connection between terminal 67 and the bimetallic element will then be made directly through element 13, screw 24 and the base of bracket 22 to the jumper 81.

In Figure 11 there is shown a wiring diagram 25 of a circuit employing the thermostatic switch of the present invention when using a heater. A step-down transformer 84 is used to supply low voltage current to the circuit. The transformer comprises a line voltage primary 85 and a low voltage secondary 86. One end of this secondary is connected to contact 17 and the other end thereof is connected to one terminal of a relay coil 88. This relay coil is associated with switch arm 89 and 90 which are adapted to engage with contacts 91 and 92, respectively, upon energization of said coil. Switch arm 90 and contact 92 control the operation of the temperature varying means; thus this contact arm and contact may control the operation of an oil burner motor, 40 a gas valve or some similar device. Contact 91 is connected to the heater 96, which in turn is connected to the bimetallic element 11. Contacts 15 and 17 are less widely spaced than contacts 14 and 16 so that upon a decrease in temperature contacts 15 and 17 are first brought into engagement. Bimetallic element 11 is adapted to move in the direction of contacts 16 and 17 upon a fall in temperature. Upon such a fall in temperature taking place, contacts 15 and 17 are 50 first brought into engagement. The engagement of these contacts, however, does not establish any circuit. If the fall of temperature continues, contacts 14 and 16 will eventually be brought into engagement by reason of the fact, 55 that contact 15 is mounted on a yieldable arm 57 as shown and described in connection with Figure 6. Upon the engagement of contacts 14 and 16, the following energizing circuit is established: From secondary 86 through conductor 93, contacts 17 and 15, contacts 14 and 16, conductor 94, conductor 95, relay coil 88 and conductor 115 back to the secondary 86. The establishment of this energizing circuit results in relay coil 88 being energized and causing the engagement of contact arms 89 and 90 with contacts 91 and 92, respectively. The engagement of switch arm 90 with contact 92 completes the circuit of the temperature varying means. The engagement of contact arm 89 with contact 91 70 establishes a holding circuit for relay coil 88. This holding circuit is as follows: From secondary 86, through conductor 93, contacts 17 and 15, bimetallic element 11, heater 96, conductor 147, contact 91 and switch arm 89, conductor 95, 75

relay coil 88, conductor 115 back to the secondary 86. Thus, so long as both contacts 15 and 17 and contacts 14 and 16 are in engagement there will be two parallel circuits through coil 88, one of these circuits including the heating element 96 and the other of these circuits being merely across the contact carrying portion of the thermostat. Since the former circuit is of much higher resistance because of the presence of the high resistance heating element very little current will flow through this circuit. As the temperature of the space arises due to the operation of the temperature varying means, the thermostat 11 will be gradually deflected in that direction tending to move contacts 14 and 16 away from contacts 15 and 17. After this action has continued for a short time contacts 14 and 16, which as previously mentioned are more widely spaced, will be moved out of engagement, leaving contacts 15 and 17 still in engagement. When this takes place the only circuit through relay coil 88 is through the heater 96 so that a large current will flow through the heater. This will cause the heating element to raise the temperature adjacent the thermostat with the result that in a comparatively short period of time, the thermostat 11 is deflected sufficiently away from contacts 15 and 17 that the disengagement of contacts 15 and 17 is effected. It will be seen that the effect of the heater 96 is to accelerate the breaking of the contacts of the thermostatic switch after the temperature in the space has begun to rise by reason of the operation of the temperature varying means. By reason of the sequential engagement of contacts 15 and 17 and 14 and 16, a chattering action is avoided in that very slight movement of the thermostat 11 to the right will not put into operation the temperature varying means, nor after both pairs of contacts are in engagement will a slight but temporary temperature rise sufficient only to cause disengagement of contacts 14 and 16 momentarily, cause the temperature varying means to be put out of operation. However, when the rise in temperature is not merely a temporary one, but is indicative of gradually rising temperature by reason of the operation of the temperature varying means the heater 96 functions to cause a more rapid disengagement of the thermostatic contacts so as to lessen the danger of the temperature rising above the optimum temperature. If such a means is not provided it is quite common for the temperature to rise a number of degrees above the desired temperature after the thermostat has put out of operation the temperature varying means, due to the time lag between the production of the heat in the furnace and the delivery of the same to the room or space to be heated.

As will be more or less obvious from the preceding description, the temperature differential required to bring into engagement contacts 14 and 16 after engagement of contacts 15 and 17 is the differential permitted between circuit opening and closing positions. The dial 51 serves as a means for indicating this differential. In initially adjusting the thermostat the dial 51 is turned to a position wherein the pointer 52 is opposite the numeral corresponding to the desired number of degrees temperature differential. Contact screw 48 is then adjusted so that upon turning the scale 29 through the number of degrees indicated on the dial 52, the bimetallic element will be moved from a position in which only contacts 15 and 17 are in engagement to a

position wherein both pairs of contacts are in engagement. After this is done, the adjustment of the cam 21 with respect to the scale 29 may be made by the means previously described so that the scale 29 indicates the temperature at which engagement of contacts 15 and 17 takes place. When this is done, the scale 29 may be turned to any desired temperature setting and locked therein by the locking member 39. The thermostat will thus be provided with means for both indicating the temperature at which the thermostat will operate and the temperature differential required to effect such operation.

In Figures 12 and 13 there is shown a modified form of a condition responsive switch. This form of the switch differs structurally from the previously described one only in the arrangement of the contacts. Instead of the bimetallic element carrying a pair of contacts which sequentially engage stationary contacts, the bimetallic member carries a switch arm which is movable between two opposed contacts. Referring to the figure, the bimetallic element is here designated by the reference numeral 100 and has attached thereto a switch arm 101. This switch arm is provided with two contact members 102 and 103 on opposite sides thereof, which contact members are adapted to engage with contacts 104 and 105, respectively. Contact 105 is rigidly and non-adjustably secured to a forwardly extending arm 106 of a bracket 107 corresponding to bracket 41 of the previously described form. Contact 104 is in the form of a slotted, threaded member 108 which is threaded into an internally and externally threaded bushing 109 which is most clearly shown in Figure 14. Bushing 109 is provided with a scale 110 which is provided with numerals on the face thereof in a manner similar to dial 51 of the preferred species. Bushing 109 is located within a screw-threaded aperture in a forwardly extending arm 111 of a bracket 112. The forwardly extending arm is slotted, as indicated in dotted lines in Figure 12, at 113. As in the previous species, the slotting of this arm is for the purpose of making the same resilient and causing the same to tightly engage the number 109. The arm 111 is provided with a pointed projection 114 which cooperates with the scale 110 to indicate the setting thereof. In initially adjusting the device the bushing 109 is rotated in the arm 111 by means of a slot in the head thereof until the value of the temperature differential desired is indicated on the scale 110 opposite the pointer 114. Screw 108 is then turned within the bushing 109 until the spacing between contacts 104 and 105 is such that the temperature differential indicated on the scale 110 is necessary to cause movement of switch arm 101 from engagement with contact 104 into engagement with contact 105. When this is done the setting of the scale 110 is an indication of the temperature differential at which the apparatus is set to operate.

In Figure 15 there is shown the condition responsive switch mounted within its cover. In the form shown, the condition responsive switch 65 is a thermostatic switch and a thermometer 116 is located within the cover 117 back of an opening 118 therein so as to be visible from the front of the cover. Adjacent the opening are graduations indicating degrees of temperature. The cover 117 is provided with a slot at the upper end thereof through which the scale 29 projects so as to make the thermostatic switch readily adjustable without removing the cover. As shown in Figure 16, the cover is retained in position 75

upon the switch by means of a screw 119 which extends through a slot 120 in said cover and is in threaded engagement with the switch base 12. The front portion of the cover 117 is constituted by a central projecting portion 139 and two side portions 140 and 141. The side portions are open at the top and bottom to facilitate the passage of air adjacent the switch. In the upper edge of the central portion of the case, a grilles opening is provided by striking out portions of the cover. These portions 121 and 122 are utilized to retain the thermometer in place as indicated in Figures 17 and 19 and as will be presently described. The thermometer 116 is mounted upon a strip 123, shown most clearly in Figure 18. This strip is provided at its upper end with a transversely extending strip 124 whose ends 125 are turned inwardly. The lower end of the strip is enlarged as at 126 and terminates in a slotted end portion 127 of relatively narrow width. The enlarged portion 126 of the strip is provided with an opening 128 therein and adjacent the upper end thereof there are two inwardly directed prongs 129. The thermometer 116, as is usual, is provided with a bulb 130 at its lower end and at its upper end is provided with a turned sealed tip 131. This tip 131 projects through an opening 132 in strip 123 and is sealed thereto by sealing material 133. The bulb of the thermometer projects through the opening 128. The stem portion of the thermometer extends between the tongues 129. As most clearly indicated in Figure 19 the opening 118 in the cover 117 is formed by striking inwardly a portion thereof leaving two inwardly extending strips 134 and 135. The thermometer stem is located between these two strips and is held in position thereagainst. At its lower end the cover 117 is provided with an upwardly extending strip 136 which strip is provided with a screw-threaded aperture adapted to receive a screw 137. Screw 137 serves as a means for securing the strip 123 with its associated thermometer 116 in position. As previously mentioned, this strip is slotted so as to permit initial adjustment of the thermometer and strip in a vertical direction until the thermometer is in a proper position relative to the scale on the cover. When this adjustment is obtained the screw 137 is tightened to prevent any further vertical movement of strip 123 and sealing material 133 is employed to prevent this adjustment being disturbed. The upper end of strip 123 is retained in position by means of strips 121 which engage with the transverse portion 124 of strip 123 and hold the same in position with the inwardly directed ends 125 abutting the inner surface of the cover 117. As will be readily seen from the foregoing description, the thermometer, after the initial adjustments have been made, is permanently and securely held in position by a construction which is relatively simple.

It will be seen that a condition responsive switch has been provided in which provision is made for all desired adjustments through a simple, compact structure which is relatively free from damage by careless installation, and in which all adjustments can be locked to prevent accidental disturbance thereof. The invention further provides a thermostatic switch employing a heater, in which the heater element is of relatively simple construction employing the securing means therefor both as mechanical securing means and electrical connecting means. At the same time, provision is made for very simply removing the heater and adapting the thermostat

for operation of the same without any alterations thereof. There is further provided a mounting structure for a switch of this type wherein the switch is resiliently secured to the mounting structure to prevent any damage to the base of the switch. There is further provided a new and novel switch cover structure in which the thermometer is held within the cover where it is not so easily damaged by a relatively simple holding structure which employs elements which are struck out of the cover for other purposes.

While two specific embodiments of this invention have been described, it will be understood that these are for purposes of illustration only, and that the invention is to be limited only by the scope of the appended claims.

We claim as our invention:

1. In a thermostatic switch, a base member, a temperature responsive element, means pivotally mounting said temperature responsive element for movement perpendicularly to said base, an adjusting cam having a helical surface and rotatably mounted on said base with the axis of the helix extending perpendicularly to said base, said temperature responsive element comprising an elongated member engaging said cam surface and extending parallel to a line tangent to the cam surface at the point of engagement of said elongated member therewith and which elongated member is substantially perpendicular to a line intersecting the said axis and the cam surface at the point of engagement with said elongated member.

2. In a thermostatic switch, a base member, a temperature responsive element in the form of a flat strip of material bent at an intermediate point to form a U-shaped member, means mounting said temperature responsive element for pivotal movement perpendicularly of said base, a fixed contact secured to said base, a contact on one leg of said U-shaped temperature responsive element adapted to be engaged with said fixed contact upon said element being subjected to a temperature of predetermined value, and means for adjusting the value of the temperature at which engagement takes place, said means comprising a member having a helical cam surface rotatably mounted on said base with the axis of said helical cam surface disposed perpendicularly to said base, the other leg of said thermostatic element engaging said cam surface and being disposed parallel to a line tangential to said cam surface at the point of contact of said leg therewith, and which is substantially perpendicular to a line intersecting the said axis and the cam surface at the point of engagement with the said leg.

3. In combination, a base, a switch mounted on said base, switch adjusting means comprising a rotatable cam member, a scale member rotatable about a common axis with said cam member and means for adjustably securing said scale member to said cam member for rotation therewith, an indicator fixedly secured to said base and cooperating with said scale member to give an indication of the setting of said adjusting means and to limit the range of movement of said means.

4. In combination, a base, a switch mounted on said base, switch adjusting means comprising a cam member rotatably mounted in said base, a scale member rotatably mounted in said base and having an arcuate slot therein, means for adjustably securing said scale member to said cam member for rotation therewith, an indicator fixedly secured to said base and projecting

through the arcuate slot in said scale member to cooperate therewith to give an indication of the setting of said adjusting means and to limit rotation of said cam and scale members by engagement with the ends of said slot.

5. In combination, a base, a switch mounted on said base, switch adjusting means comprising a cam member rotatably mounted on said base, a scale member rotatably mounted on said base and having an arcuate slot therein, means for adjustably securing said scale member to said cam member for rotation therewith, yieldable means for preventing unimpeded rotation of said cam member, said means comprising an elongated member projecting through the arcuate slot in said scale member to give an indication of the setting of said adjusting means and to limit rotation of said cam and scale members by engagement with the ends of said slot.

10. 6. In combination, a base, a switch mounted on said base, switch adjusting means comprising a cam member rotatably mounted in said base, a scale member rotatably mounted in said base, means for adjustably securing said scale member to said cam member for rotation therewith, an indicator fixedly secured to said base and located adjacent to said scale member to give an indication of the setting of said adjusting means, and clamping means to lock the cam and scale members in any desired adjusted position.

7. In combination, a mounting plate, means for securing the mounting plate to a supporting surface, connecting terminals on said plate adapted to engage the ends of electrical conductors, a base, a switch on said base, terminals on said base electrically connected to said switch, spring fingers secured to the terminals on said base, and means for securing said spring fingers to the connecting terminals on said mounting plate to connect electrically the base terminals to the mounting plate terminals and to resiliently support the base and switch whereby the formation of stresses in the base is prevented, said spring finger forming the sole supporting means for said base.

8. In a condition responsive mechanism, a condition responsive switch, a cover for said switch, said cover having an opening therein, a condition indicating device, means for mounting said device within said cover in a position such that it is visible through the opening, said means comprising an elongated member to which said indicating device is attached, and inturned portions on said cover retaining said member and attached indicating device in position.

9. In a condition responsive mechanism, a condition responsive switch, a cover for said switch, said cover having an opening therein, a condition indicating device, means for mounting said device within said cover in a position such that it is visible through the opening, said means comprising an elongated strip to which said indicating member is attached, a plurality of inturned tongue members struck out of said cover to provide an opening therein for the admission of air to the switch and engaging said strip to retain it and said indicating member in position, at least one of said tongue members having means associated therewith for rigidly securing said strip and attached condition indicating member in any desired position with respect to said opening.

10. In combination, a base, a thermal responsive switch mounted on said base, an electrical heater located near the switch and adapted to

modify the action of said switch, a terminal on said base, means electrically connecting one terminal of said heater to an element of said switch and means for attaching said heater to said base, said attaching means serving to connect the other terminal of said heater to said terminal on said base.

11. In combination, a base, a thermal responsive switch mounted on said base, an electrical heater located near the switch and adapted to modify the action of said switch, a terminal on said base, a housing for said heater, said housing electrically connecting one terminal of said heater to an element of said switch and means for attaching said housing to said base, said attaching means serving to connect the other terminal of said heater to said terminal on said base.

12. In combination, a base, a condition responsive switch comprising two switch members and a condition responsive element for moving said members into and out of engagement, means for adjusting the value of the condition at which engagement of said contacts takes place comprising a disc rotatably mounted with respect to said base, locking means for said disc comprising two clamping members disposed on opposite sides of said disc, means for clamping said members against said disc, and means on said base to prevent displacement of said clamping members in the direction of rotation of said disc.

13. In a thermostatic switch, a base member, a substantially U-shaped thermostatic element, means mounting said thermostatic element for movement perpendicularly of said base member, a fixed contact secured to said base member, a contact operated by said U-shaped thermostatic element for engaging said fixed contact upon said element being subjected to a temperature of predetermined value, and means for moving said U-shaped thermostatic element for adjusting the value of the temperature at which engagement takes place, said means including a rotatable member mounted on said base member and having a helical cam surface, the axis of rotation of said member being perpendicular to said base member, and friction means associated with said rotatable member for holding said member in its rotatably adjusted positions.

14. In a thermostatic switch, a base member, a substantially U-shaped thermostatic element, means mounting said thermostatic element for movement perpendicularly of said base member, a fixed contact secured to said base member, a movable contact carried by one leg of the U-shaped thermostatic element and adapted to engage and disengage said fixed contact at predetermined temperature values affecting said U-shaped thermostatic element, said thermostatic element moving said movable contact toward and away from said base member upon changes in temperature, and means operatively associated with the other leg of the U-shaped thermostatic element for moving said thermostatic element perpendicularly of said base member for adjusting the temperature values at which said contacts engage and disengage, said means including a rotatable member mounted on said base member and having a helical cam surface, the axis of rotation of said member being perpendicular to said base member, an arcuate groove in said rotatable member, and a projection carried by said base member extending into said arcuate groove to limit rotation of said rotatable member.

15. In a thermostatic switch, a base member, a thermostatic element in the form of a strip bent at an intermediate point to form a temperature responsive device having two substantially parallel legs, means mounting said temperature responsive device on said base member for movement about an axis parallel to said base member and with the legs arranged substantially parallel to said base member, one leg being more remote from the base member than the other, a fixed contact secured to the base member, a movable contact carried by the more remote leg of the temperature responsive device and movable toward and away from the fixed contact upon temperature changes affecting the thermostatic element, and means operatively associated with the less remote leg of the temperature responsive device for moving the temperature responsive device about an axis parallel to the base member whereby the temperature setting of the thermostatic switch is adjusted, said last mentioned means including a rotatable member mounted on said base member and having a helical cam surface, the axis of rotation of said member being perpendicular to said base member, and means associated with said base member for limiting rotation of said rotatable member.

16. In a thermostatic switch for controlling an apparatus, a base member, a substantially U-shaped thermostatic element, means mounting the thermostatic element on said base member, a pair of fixed contacts secured to said base member and located on the same side of the thermostatic element, a pair of movable contacts carried by one leg of the U-shaped thermostatic element and adapted to engage and disengage said fixed contacts at predetermined temperature values affecting said U-shaped thermostatic element for closing and opening a circuit across said fixed contacts and turning on and off the apparatus, said thermostatic element moving said movable contacts toward and away from said base member upon changes in temperature, means for adjusting one of said fixed contacts for adjusting the temperature value at which said contacts engage and disengage, and means for indicating the adjustment of said adjustable fixed contact said means including a member with a plurality of markings thereon, a member with a single marking thereon, the single marking cooperating with the plurality of markings for performing the indicating function and means for operating one of the members upon adjustment of said adjustable fixed contact.

17. In a condition responsive mechanism, a condition responsive controlling mechanism, a cover for said mechanism having an elongated opening therein, flanges along the edges of the opening inside of the cover, an elongated condition indicating device in said cover engaging said flanges, an elongated strip coextensive with the elongated indicating device for holding the indicating device against said flanges, and means for securing the extremities of the elongated strip to the cover.

18. In a condition responsive mechanism, a condition responsive controlling mechanism, a cover for said mechanism having an elongated opening therein, flanges along the edges of the opening inside of the cover, an elongated condition indicating device in said cover engaging said flanges, an elongated strip coextensive with the elongated indicating device, means for fastening said indicating device to said strip, and means for securing the extremities of the strip to said

cover for holding the indicating device in a predetermined position against said flanges.

19. In a condition responsive mechanism, a condition responsive controlling mechanism, a cover for said mechanism having an elongated opening therein, flanges along the edges of the opening inside of the cover, an elongated condition indicating device in said cover engaging said flanges, an elongated strip coextensive with the elongated indicating device, means for fastening 10 said indicating device to said strip, and means for securing the extremities of the strip to said cover for holding the indicating device in a predetermined position against said flanges, said last mentioned means including means for longitudinally adjusting the strip and indicating device with respect to said opening.

20. In a thermostatic device, a cover, an indicating thermometer, an opening in said cover and means for securing the thermometer to the inside of the cover so as to be visible from the outside including an elongated strip engaging the thermometer, a lug carried by the cover to be engaged by one end of the strip to secure that end of the strip to the cover, and a fastening means 25 for securing the other end of the strip to the cover and for holding the first mentioned end in engagement with the lug.

21. In a thermostatic switch, an elongated base, a switch operating element comprising a strip 30 of bimetallic material bent transversely into the form of an elongated U-shaped member, means mounting said member for movement with respect to said base, the U-shaped member being mounted diagonally with respect to the length of 35 said base, and a cover for said base enclosing said member, said cover having openings therein to facilitate the circulation of air past said member.

22. In a device of the character described comprising in combination, a base member, an elongated thermostatic element bent transversely at a portion intermediate the ends thereof, first switch means carried by said base member, second switch means moved by one end of said 40 thermostatic element for engagement with said first switch means upon changes in temperature affecting the thermostatic element, an adjusting member rotatably mounted on said base including a cam, means for mounting the thermostatic element on said base for movement with respect to said cam and for resiliently biasing the thermostatic element to position the other end thereof as determined by said cam member, one of said 45 base and adjusting members having a cut-away portion and the other of said members being provided with a projection extending into the cut-away portion to limit the rotation of the adjusting member.

23. In combination, a base, a switch mounted 50 on said base, switch adjusting means comprising a cam member rotatably mounted in said base, a scale member rotatably mounted in said base, means for adjustably securing said scale member to said cam member for rotation therewith, a 55 fixedly mounted indicator located adjacent to said scale member to give an indication of the setting of said adjusting means, and clamping means to lock the cam and scale members in any desired adjusted position.

24. In a device of the character described comprising in combination, a base, a thermostatic switch mounted on said base, a cover for said switch adapted to be supported by said base, said cover having an elongated opening in the face 70 75

- thereof, an indicating thermometer, an elongated strip, means for connecting said thermometer to said strip, and means for mounting said strip to the inside of said cover so that said thermometer 5 will be visible through the opening in said cover.
25. In a device of the character described, comprising in combination, switch means, a thermostat responsive primarily to variations in temperature of the surrounding atmosphere for actuating said switch means, an electric heater controlled by said switch means, said thermostat being operative to automatically energize and deenergize said heater, and means comprising a predetermined mass of heat absorbent material 10 which must first be heated by said heater before the heat is transmitted to raise the temperature of said thermostat above that of the surrounding atmosphere a predetermined time after energization of said heater.
- 10 26. In a temperature responsive switch, a base, a thermostat on said base, a switch actuated by said thermostat, a cover for said thermostat and switch, an opening in said cover, a thermometer within said cover and visible through said opening, means on said cover for supporting said thermometer within said cover in a position that is adjustable with respect to said opening, and in such a position as to be visible through said opening.
- 15 27. In a device of the character described comprising in combination, a base, a thermostat mounted on said base, a switch actuated by said thermostat, adjusting means for said thermostat comprising a cam rotatably mounted in said base, a graduated dial connected to said cam so that the latter may be rotated by the former, an arcuate slot in said dial, and a resilient member for resisting rotation of the dial, said resilient member having an arm which extends through said arcuate slot in said dial, and a cover for said thermostat and switch, said cover fitting over said base, and a slot in the top of said cover through which said dial and pointer extend when said cover is in place over said base.
- 20 28. In a device of the character described comprising in combination, a base, a thermostat mounted on said base, a switch actuated by said thermostat, an adjusting member rotatably mounted on said base, an adjusting cam for said thermostat fixed on said member, a graduated dial fixed on said member, an arcuate slot in said dial, a resilient member engaging said base and resisting the rotation of said dial, means on base for preventing rotation of said resilient member, and an arm on said resilient member extending through said arcuate slot in the form of a pointer for cooperation with the graduations on said dial, said arm also limiting the manual rotation of said dial by engagement with the ends of the slot.
- 25 29. In a device of the character described comprising in combination, a base, a thermostat mounted on said base, a switch actuated by said thermostat, adjusting means for said thermostat comprising a cam rotatably mounted in said base, a graduated dial connected to said cam so that the latter may be rotated by the former, an arcuate slot in said dial, a resilient member for resisting rotation of the dial, said resilient member having an arm which extends through said arcuate slot, and a cover for said thermostat and switch, said cover fitting over said base, and a slot in the top of said cover through which said dial and pointer extend when said cover is in place over said base.
